SANITARY NAPKIN

Find Andersen, Copenhagen, Denmark, assignor to Karl Krøyer Kristian Kobs

Filed Nov. 17, 1972, Ser. No. 307,520

Claims priority, application Denmark May 18, 1972

Term of patent 7 years

Int. Cl. D24—04

U.S. Cl. D83—1 A

FIG. 3

FIG. 1 is a top plan view of the front of the cover portion of the sanitary napkin embodying my new design.

FIG. 2 is a top plan view of the absorbent pad portion of the sanitary napkin embodying my new design.

FIG. 3 is a perspective view of a sanitary napkin embodying my new design and comprising the cover and the absorbent pad illustrated in FIGS. 1 and 2, respectively, and

FIG. 4 is a cross sectional view along the line 4—4 through the sanitary napkin illustrated in FIG. 3.

The broken lines are shown for illustrative purposes only.

I claim:

The ornamental design for a sanitary napkin, as shown and described.
